United States Patent Office

Des. 189,585
Patented Jan. 10, 1961

189,585

TRICYCLE

Harry Horowitz, New York, and Abraham Schneiderman,
Westbury, N.Y. (both of 276 Nostrand Ave., Brooklyn, N.Y.)

Filed Aug. 31, 1960, Ser. No. 61,966

Term of patent 14 years

(Cl. D34—15)

Figure 1 is a front elevational view of a tricycle showing our new design;

Figure 2 is a rear elevational view thereof;

Figure 3 is a side elevational view thereof;

Figure 4 is a top plan view thereof; and

Figure 5 is a bottom plan view thereof.

We claim:

The ornamental design for a tricycle, substantially as shown.
